UNITED STATES PATENT OFFICE

1,982,740

EDGE BURNISHING MACHINE

Frank Bycroft Keall and Charles Turner Jones,
Leicester, England, assignors to United Shoe
Machinery Corporation, Paterson, N. J., a cor-
poration of New Jersey

Application July 17, 1931, Serial No. 551,466
In Great Britain July 30, 1930

12 Claims. (Cl. 12—78)

This invention relates to shoe finishing machines and is illustrated herein as embodied in an edge setting device adapted for use in connection with an automatic edge setting machine of the type disclosed in United States Letters Patent No. 5 1,693,634, granted December 4, 1928, on application of Barclay and Keall.

In many shoes the edges of the sole at the shank are disposed at different angles to the tread face thereof at either side of the shank; that is, at the outer side of the shank the sole edge is usually straight heightwise thereof and approximately at right angles to the tread surface of the sole, and at the inner edge of the shank 15 the edge of the sole is usually oblique to the tread surface of the sole and somewhat curved heightwise thereof. It is therefore desirable in finishing shoes of the above type to use a multi-faced tool, such for example as one of the type disclosed in 20 United States Letters Patent No. 1,685,368, granted September 25, 1928, on application of T. Lund, which tool has work engaging surfaces adapted for operating on both the outer and inner sole edges of shoes of the above type.

It is desirable, furthermore, that a sole edge 25 may be presented to either of the work engaging faces of a tool of the above type in substantially the same position, and to this end various devices have been made for effecting a movement of a tool holder for such a tool between two operative 30 positions so that either of the work engaging faces of the tool may be brought into operative position.

In view of the foregoing, a feature of the invention 35 consists in the provision in a burnishing machine of a tool carrier, a tool holder mounted for movement in said carrier between two operative positions, and means mounted for reciprocation constructed and arranged both to move said 40 holder between and to hold it in its two operative positions.

Considered in another aspect, invention is to 45 be recognized in mounting the above-mentioned means for moving the holder between its operative positions in the carrier so as to have driving engagement with the holder substantially at the axis of oscillation of the carrier, whereby the 50 difficulty of providing operating connections with the holder turning means owing to the oscillating movement of the latter is minimized. For the sake of convenience to the operator, it has been found desirable to have the tool holder so mounted 55 that it not only can be moved between two operative positions as pointed out above but also is normally held in one of its operative positions,

which has been termed herein the "normal" operative position, and is automatically returned thereto from the other operative position. Accordingly, another feature of the invention 60 consists in the provision of means arranged yielding to act upon the bar, thereby to cause the holder which is controlled by the bar to be held in its normal operative position. The limits of movement of the above-mentioned bar which correspond to the operative positions of the tool holder 65 are determined by means for operating the bar having a predetermined limited movement. Thus, when the bar is held at either limit of its movement by either the operator or the above-mentioned yielding means, the tool holder is held in 70 one or the other of its operative positions. Preferably gear connections are provided between the tool holder and the bar, the holder having gear teeth arranged for meshing engagement with teeth on the bar, herein shown as a rack bar. 75

These and other features of the invention are described in the following specification and are illustrated in the accompanying drawings, in which

Fig. 1 is an elevation showing one machine in 80 which the invention is embodied,

Fig. 2 is a plan view of a part of the machine illustrated in Fig. 1, and

Fig. 3 is a sectional elevation of the structure shown in Fig. 2.

The said automatic edge setting machine will 85 be assumed to be of the type disclosed in the specification of the Barclay and Keall Patent No. 1,693,634 mentioned above, and the frame 10 of this machine, which is oblong in plan and has its 90 longer dimension running from right to left of the operator, has bolted to it on its right-hand front corner a bracket 12 on the top of which is secured a column 14 bearing at its upper end a frame member or head 16 carrying the shank edge setting mechanism forming the subject-matter of the present invention. The bracket 12 has at its lower end, extending from it toward the right and rearwardly of the automatic machine, a platform 18, about one foot from the floor, on which is mounted an electric motor 20 for driving the shank edge setting mechanism. The shank setting mechanism may, however, be driven by belt and pulleys from the driving shaft of the automatic edge setting machine.

The shank edge setting mechanism comprises a single edge setting tool 22 which is formed with two work engaging surfaces. These surfaces are respectively formed to operate on a square edge and a rounded edge of a sole at the shank, the 110

tool being therefore similar to that shown in Fig. 4 of the Lund Patent No. 1,685,368 referred to above, and the tool 22 may be turned through an angle of 180 degrees about an axis (the axis of its shank 24) extending perpendicularly to the square edge surface so as to bring the desired edge setting surface into operative position. The lower operative end of the shank edge setting tool 22 is positioned preferably some twenty inches to the right from the edge setting tool of the automatic machine when viewed from the front of the automatic machine and is about eighteen inches in from the latter tool. The lower end of the shank edge setting tool is clamped in the lower end of a tool holder 26 with the axis of the shank 24 of the iron 22 coaxial with the holder 26. The axis of the holder 26 extends upwardly and rearwardly at an angle of about twenty degrees to the vertical and the said axis when viewed from above lies at an angle of about twenty-five degrees to the front of the automatic machine and extends from the lower face of the edge setting tool rearwardly and to the right of the front of the automatic machine. By thus arranging the position of the shank edge setting mechanism in relation to the automatic machine, the operator of the automatic machine, after he takes a shoe from the latter and has replaced it by an unfinished one, can present that removed from the automatic machine to the shank edge setting mechanism, by merely a turning movement through, roughly, ninety degrees.

The holder 26 which carries the shank edge setting tool 22 is tapered and split at its lower end and has on it a sleeve 28 in threaded engagement with a threaded portion 30 of the holder 26 above the tapered portion. The sleeve 28 at its lower end has an internally tapered portion corresponding to the tapered portion of the holder 26, and the sleeve 28 has clamped on it a hand lever 32 by which the sleeve may be rotated and, by reason of the threaded portions, moved endwise on the spindle to cause, through the co-operating tapered portions, the lower split end of the holder to clamp the shank of the tool in the bored end of the holder. The holder 26 and sleeve 28 are rotatably mounted in a carrier 34 which has extending integrally from it a horizontal carrier shank 36 rotatably mounted in the frame 16 of the shank edge setting mechanism. The axis of the carrier shank 36 and the tool holder axis are parallel when viewed from above. The carrier 34 is gashed at its front to receive and support the hand lever 32. The upper end of the holder 26 is bored axially to receive a ball 38 which is engaged by the lower end of an upwardly extending rod 40. The rod 40 is slidably mounted in the frame 16 of the mechanism and is pressed downwardly by an adjustable spring 42 in the frame. This rod and spring arrangement and the carrier and its horizontal shank are all substantially similar to the corresponding parts disclosed in United States Letters Patent No. 979,249, granted December 20, 1910, on application of Arthur Bates, and the spring arrangement allows the edge cutting tool to yield slightly under the pressure of the work against it.

The carrier shank 36 has fixed on its rear end a bearing member 44 and the bearing member has fixed in its rear end a short shaft 46, in axial alignment with the carrier shank 36, which is rotatably mounted in the frame 16 of the edge setting mechanism. The bearing member 44 has rotatably mounted in it a swivel member 48 the axis of which extends vertically at right angles

to and intersects the axis of the carrier shank 36. The swivel member 48 has a substantially horizontal bearing 50 for an angled portion 52 of a driving shaft 54 for the edge setting mechanism. The axis of this bearing which intersects the vertical axis of the swivel member 48 is substantially at right angles to the axis of the carrier shank 36 and about half an inch above the latter axis. The axis of the portion of the driving shaft 52 in the bearing 50 of the swivel member 48 is at an angle of about one and a quarter degrees to the extended axis of the driving shaft 54 and the point on the extended axis of the driving shaft where the axis is coincident with the intersecting point of the extended axis of the driving shaft and the axis of the swivel member 48. The driving shaft 54 has fixed to it a pulley 56 which is driven from the electric motor 20 or from the driving shaft of the automatic edge setting machine. When the driving shaft 54 is rotated the tool 22 is oscillated about the axis of the carrier shank 36, the mechanism for oscillating the tool being substantially similar to the mechanism and operating in the same manner as that described in United States Letters Patent No. 1,035,445, granted August 13, 1912, on application of A. E. Jerram.

The edge setting tool holder 26 has formed around it gear teeth 58 (Fig. 3) which mesh with rack teeth 60 formed on the forward end of a horizontal bar 62 extending through the carrier shank 36 and short shaft 46 coaxially therewith. The rear end of the bar 62 has on it a grooved collar 64 within the groove of which is received a pin 66 extending from one arm 68 of a bell-crank lever 70 pivoted on the frame 16 of the shank edge setting mechanism. The other arm of the bell-crank lever 70 is connected to a treadle 72 pivoted on the bracket 12 by means of a treadle rod 74, and stop screws 76, 78 on the bell-crank lever engage stop faces on the frame 16 to limit the movement of the bell-crank lever in both directions and hence position the tool holder in both its normal and alternative operative positions. A spring 80 abutting the collar 64 and the frame 16 constantly urges the tool holder toward its normal operative position and normally holds the stop screw 76 against its stop face. When the treadle is depressed the tool holder 26 and the tool 22 are rotated to their alternative operative position. The stops 76 and 78 are so adjusted that the holder can be rotated through 180 degrees, the angle between the work engaging faces of the illustrated tool. The tool, as has been stated, has two edge setting surfaces, one for operating on square edges and the other on rounded edges. One of these surfaces is normally held in the operative position and by depressing the treadle 72 and holding it depressed the other surface may, by rotation of the tool about the axis of its shank, be brought into the operative position and held there. If the tool has associated with its square edge surface a stitch wheel the rounded surface is positioned about half an inch below the level of the square surface so that when setting by the rounded surface close up to the heel breast the wheel shall be above the level of the edge of the sole and shall not mark the heel.

Having thus described our invention what we claim as new and desire to secure by Letters Patent of the United States is:

1. In an edge burnishing machine, a tool car-

- rier, a tool holder mounted for movement in said carrier between a normal and another operative position, a slide mounted in said carrier for moving said holder between its operative positions, and means acting upon said slide for yieldingly resisting the movement of the holder from its normal position and for causing the slide to return said holder to its normal operative position from its said other operative position. 5 80
- 10 2. In an edge burnishing machine, an oscillating tool carrier, a tool holder rotatably supported in said carrier, and means supported by said carrier for turning said holder adapted for engagement with the holder substantially at the axis of oscillation of the carrier. 85
- 15 3. In a burnishing machine, a tool carrier having a shank, a tool holder mounted to rotate in said carrier between a normal and an alternative operative position, a movable bar arranged to rotate said holder, a spring acting upon said bar thereby to urge said holder toward its normal operative position, and means for operating said bar having limited movement in opposite directions whereby the holder is positioned definitely in both its normal and alternative operative positions. 90
- 20 4. In an edge burnishing machine, an oscillating tool carrier, a tool holder mounted for movement in said carrier between two operative positions, and means connected to said holder substantially at the axis of oscillation of the carrier constructed and arranged both to move said holder between and to hold it in its two operative positions. 95
- 25 5. In an edge burnishing machine, an oscillating tool carrier, a tool holder rotatably supported in said carrier, a bar disposed substantially coaxially with respect to the axis of oscillation of the carrier and operatively connected to said holder, and operator-controlled mechanism for operating said bar thereby to cause a movement of said holder between two operative positions. 100
- 30 6. In an edge burnishing machine, a tool carrier, a tool holder mounted for movement in said carrier between two operative positions, and a bar having driving engagement with said holder constructed and arranged to move said holder between and hold it in its operative positions. 105
- 35 7. In an edge burnishing machine, an oscillating tool carrier, a tool holder rotatably supported in said carrier, a bar operatively connected to said holder, and means for operating said bar substantially in the direction of the axis of oscillation of the tool carrier to cause a movement of said holder between two operative positions. 110
- 40 8. In an edge burnishing machine, a tool carrier having a shank, a tool holder rotatably supported in said carrier, a bar disposed in said shank and operatively connected with said holder, yielding means acting upon said bar to cause said holder to be held in one operative position, and means for operating said bar to a predetermined extent thereby to cause the tool holder to be moved to another operative position. 115
- 45 9. In an edge burnishing machine, a tool carrier, a tool holder rotatably mounted in said carrier, a rack bar supported by said carrier and disposed in meshing engagement with said tool holder, and means for operating said rack bar having a predetermined limited movement whereby said rack bar is caused to hold said holder in its operative positions. 120
- 50 10. In an edge burnishing machine, a tool carrier, a tool holder rotatably mounted in said carrier and having peripheral gear teeth, a rack bar meshing with the teeth on said holder, yielding means normally urging said rack bar to move said holder toward one operative position, and means for operating said rack bar to move said holder between the first-mentioned operative position and another operative position constructed and arranged also to limit the movement of the rack bar whereby the holder is positioned in either of its operative positions. 125
- 55 11. In an edge burnishing machine, a tool carrier, a tool holder rotatably mounted in said carrier, a rack bar engaging said holder for rotating it between two operative positions, yielding means urging said rack bar to cause said holder to be rotated normally toward one of its operative positions, a crank for operating said rack bar, and means on said crank for limiting its movement whereby the movement of said holder in one direction is arrested when it is at either of its operative positions. 130
- 60 12. In an edge burnishing machine, a tool carrier, a tool holder rotatably mounted in said carrier, a rack bar engaging said holder for positioning it in either of two operative positions, yielding means normally urging said rack bar to cause said holder to be rotated toward one of its operative positions, a crank for operating said rack bar, means on said crank for limiting its movement whereby the movement of said holder in one direction is arrested when it is in either of its operative positions, and treadle mechanism for operating said crank. 135
